COMBINED PERCH AND BIRD EXERCISER

Howard C. Kiehl, Sarasota, Fla.

Application June 15, 1954, Serial No. 31,000

Term of patent 14 years

(Cl. D31—2)

To all whom it may concern:

Be it known that I, Howard C. Kiehl, a citizen of the United States of America, residing at Sarasota, county of Sarasota, State of Florida, have invented a new, original, and ornamental Design for a Combined Perch and Bird Exerciser, of which the following is a specification, reference being had to the accompanying drawing, forming a part hereof.

The figure is an elevational view of a combined perch and bird exerciser showing my new design.

I claim:

The ornamental design for a combined perch and bird exerciser, substantially as shown.
